PARTITIONED MOP BUCKET

Peter J. Koch, Jericho, N.Y., assignor to Dustbane Enterprises Limited, Ottawa, Ontario, Canada, a corporation of Canada

Filed Feb. 8, 1968, Ser. No. 10,499

Claims priority, application Canada Aug. 9, 1967

Term of patent 14 years

(Cl. D49—29)

FIG. 1 is a perspective view of a partitioned mop bucket, showing my new design;

FIG. 2 is a front elevational view thereof; and

FIG. 3 is a vertical sectional view, taken substantially in the plane of the line 3—3 in FIG. 1.

The appearance of the rear and opposite side of the bucket is substantially the same as that of the front and side, respectively, as shown.

I claim:

The ornamental design for a partitioned mop bucket, as shown and described.
